FOUNDATION GARMENT

Hildegard Wipperman, Chicago, Ill., assignor to
 The H. W. Gossard Co., Chicago, Ill., a corpora-
 ration of Illinois

Application June 26, 1937, Serial No. 150,529

3 Claims. (Cl. 2—37)

This invention relates to foundation garments for women and has for its principal object to provide a combination corset and brassière which is supple and at the same time capable of controlling the figure while permitting special freedom of movement at the front so that the connected brassière and corset portions of the garment will not pull down the bust of the wearer.

In accomplishing the foregoing object I construct the corset portion of my combination garment of various light-weight elastic sections, each of which is capable of stretching in one direction only, and I combine these sections in such a way that the various tensional forces result in producing a common symmetry of action which enables the garment to support and mold the figure while permitting it to bend in any direction without in any way impairing the freedom of movement of the wearer.

Specifically, the corset portion of my garment comprises front and back sections which are composed of elastic fabric capable of stretching only in a vertical direction, and connected side sections composed of elastic fabric capable of stretching horizontally but preferably having no vertical elasticity. The horizontally stretchable side sections of the garment cooperate to fit the garment snugly upon the figure, and the horizontal tension which these side sections exert on the vertically stretchable front and back sections provides the proper control around the body while permitting perfect freedom of movement for any upright motion of the figure as, for example, when the wearer throws the upper portion of the figure back the front portion stretches to conform to the position of the body.

In addition to the foregoing advantages of supporting and molding the busts, flattening the diaphragm and confining the abdomen while permitting freedom of movement in all directions, another important advantage of this garment is that it may be made either boned or unboned, and in either case the construction is simpler and more economical as well as being more attractive and more comfortable to wear than other garments which have heretofore been proposed for the same purpose.

These and other important features and advantages of the invention will be described in connection with the accompanying drawings, in which:

Fig. 1 is a front view of a combination corset and brassière embodying the invention;

Fig. 2 is a rear view thereof;

Fig. 3 is a plan view showing the inner front

portion of the garment in open position with the side and rear sections broken away to illustrate the novel stiffening panel at the front;

Fig. 4 is a horizontal section through the front of the garment on line 4—4 of Fig. 3;

Fig. 5 is a detail section taken on line 5—5 of Fig. 3; and

Figs. 6 and 7 are front and rear views of a modified combination garment embodying the invention.

The combination garment shown in Figs. 1 to 5 comprises a brassière 1 of soft inelastic material such as lace secured to the upper edges of the corset which is composed of a front section or panel 2, a back section 3, and side sections 4 and 5 which connect the front and rear sections of the garment as best shown in Figs. 1 and 2. The corset opens at one side and is fastened about the body in any suitable manner as by means of a slide fastener 6 and by means of auxiliary hook and eye fasteners 7 which may be provided on the meeting edges of this corset if desired.

The front section 2 of the garment is made of light-weight elastic fabric which is adapted to stretch vertically but not circumferentially of 25 the garment as indicated by the arrows in Fig. 1, and the back section 3 is similarly constructed as indicated by the vertical arrows in Fig. 2. These two sections preferably have a relatively long 30 easy stretch in a vertical direction. The front section 2, however, may have a horizontally 35 stretchable elastic gore 8 in the lower central portion thereof, as is usual in foundation garments. The side sections 4 and 5 are made of elastic fabric which is adapted to stretch horizontally or circumferentially but not vertically of the garment, as indicated by the horizontal arrows 40 in the drawings.

In the garment shown in Figs. 1 to 5, flaps or 45 end sections 9 and 10 are sewn to the vertical side edges of the brassière 1 and thence down the sides of the corset to about the waistline, these flaps being composed of elastic fabric similar to that employed in the body portion of the garment but capable of stretching only in a horizontal or transverse direction as indicated by the arrows 50 in Fig. 3 of the drawings. Each of the flaps or end sections 9 and 10 has sewn to its outer ends a pair of elastic straps 12 and 13 provided with fastening means such as buttonhole tapes 14 55 which are adapted to be fastened to a button 15 which is secured adjacent the upper central portion of rear section 3 between short stays 16 as shown in Fig. 2 of the drawings. Shoulder straps 17 and 18 are attached to the upper central apices 55

of the brassière 1 and to the outer ends of the flaps 9 and 10 of the brassière as shown in Fig. 3, these shoulder straps preferably though not necessarily being composed of elastic tape.

5 If desired, the garment may be provided at the front with a stiffened lining comprising a panel 19 of inelastic material which is stitched to the vertical side edges of front panel 2 from the top of said front panel down to the point adjacent the hip line. The top of this inelastic lining 19 is attached at the center to the lace points 20 adjacent the bust line, while the lower free edges of this lining are secured to one end of the front hose supporters 21, the other ends of which are 15 secured to the lower edge of the vertically stretchable front panel 2 as shown in Figs. 1 and 3 of the drawings. Additional hose supporters 22 of conventional type may be secured directly to the lower edges of the side and rear sections of the 20 garment in the usual manner. The panel 19 may be stiffened in any suitable manner as by means of the spaced vertical stays 23 illustrated in Figs. 1 and 3 of the drawings.

The respective front and back sections 2 and 25 3 and side sections 4 and 5 of the foregoing garment may be advantageously constructed with a difference in kick or contractive force as well as length of stretch. The front and back sections 2 and 3, which stretch up and down, do not require 30 as strong a kick as the side sections 4 and 5, the side sections in most cases requiring a relatively strong kick in order to mold the figure, and this is particularly true in the case of larger figures. In the case of many garments it is advantageous 35 to provide the front and back sections with a longer stretch than the side sections which stretch around the figure. In addition, using fabrics having different contractive forces and different lengths of stretch in this manner, makes it possible to vary the sizes of the different corset sections and the relationship between the sizes of these sections. In other words, the side sections 4 and 5 of the garment need not be as narrow as shown in Figs. 1 and 2, but may be considerably 40 broader and the front and back sections 2 and 3 made correspondingly narrower by proper selection of elastic fabrics as described above. In the form shown in Figs. 1 and 2 the side sections or 45 panels 4 and 5 are relatively narrow because the fabric employed for these panels in this particular garment has a fairly long stretch and fairly light kick and a broader side panel constructed of such fabric would not provide the proper figure control.

50 From the foregoing description it will be seen that the tension exerted by the horizontally stretchable side sections 4 and 5 of the garment results in fitting the garment smoothly upon the figure and exerts the necessary tension upon the 55 horizontally rigid front panel 2 to flatten the diaphragm and abdomen. At the same time, the tension of the horizontally stretchable brassière flaps 9 and 10 and of the diverging pairs of elastic straps 12 and 13 exerts a yielding pull along the 60 front portion of the corset which is adapted to cover the diaphragm and abdomen as well as across the brassière 1 and the upper portion of front section 2, thereby holding the brassière 65 snugly against the body of the wearer above and below the busts and further increasing the control and flattening effect upon the diaphragm and abdomen of the wearer. When the wearer throws the upper portion of the body back, the front section 2 stretches and readily conforms to 70 the position of the body without exerting any

vertical downward pull such as would tend to pull down the bust of the wearer, while at the same time the vertical extensibility of the front and back sections 2 and 3 prevents the garment from riding up on the body when the wearer is seated or assumes any other position.

5 The special floating arrangement of the front panel 19, and its connection to the hose supporters 21, permit this panel or lining to slide up when the body is thrown back, and when the body 10 straightens again this lining is automatically pulled back into position without in any way shifting the position of the garment on the figure.

The modified garment shown in Figs. 6 and 7 comprises a brassière 25 of soft inelastic material, 15 and front and back elastic sections 26 and 27 connected by side elastic sections 28 and 29. The front and back sections 26 and 27 are composed of light-weight elastic fabric capable of stretching vertically but not horizontally, while 20 the side elastic sections 28 and 29 are composed of similar fabric capable of stretching horizontally or circumferentially but not in a vertical direction, the garment in this respect being identical with that previously described. 25 Shoulder straps 30 and 31, which may be of elastic or inelastic tape, are connected to the upper central edges of the brassière pockets and to the upper edge of the rear section 27 of the corset. Horizontally stretchable elastic gores 32 30 and 33 are provided in the lower central portion of front section 26 and in the upper central portion of back section 27, respectively. In this garment, as in that described above in connection with Figs. 1 to 5, the various one-way stretch 35 panels, the front and back panels stretching only in a vertical direction and the side panels stretching only in a horizontal or circumferential direction, cooperate to produce a symmetry of action which enables the garment to support and mold 40 the figure while permitting it to bend in any direction without discomfort to the wearer and without causing the garment to ride up or change its position under any conditions of use.

It will be evident that various changes may be 45 made in the details of construction herein shown and described and therefore the invention is to be limited only by the scope of the appended claims when interpreted in view of the prior art.

The invention claimed is:

1. A foundation garment for women comprising a combination corset and brassière, said corset having front and back sections composed of elastic fabric capable of stretching only in a vertical direction so as to prevent said corset from 55 pulling the brassière down when the body is bent backward or forward, side sections connecting the front and back sections of said corset and composed of elastic fabric capable of stretching only in a horizontal direction so as to tension said 60 corset across the front and back of the body, a stiffening panel lining the interior of said front corset section and being connected thereto only at the vertical side edges and at a point adjacent the lower central edge of said brassière, and 65 elastic garter straps connected to the lower edges of said stiffening panel and said front corset section to permit said stiffening panel to slide up and down with bending movements of the body.

2. A foundation garment for women comprising a combination corset and brassière, said corset having front and back sections composed of elastic fabric capable of stretching only in a vertical direction so as to prevent said corset from pulling the brassière down when the body is bent back- 70 75

ward or forward, side sections connecting the front and back sections of said corset and composed of elastic fabric capable of stretching only in a horizontal direction so as to tension said corset across the front and back of the body, a stiffening panel lining the interior of said front corset section and being connected thereto only at the vertical side edges and at a point adjacent the lower central edge of said brassière, elastic garter straps connected to the lower edges of said stiffening panel and said front corset section to permit said stiffening panel to slide up and down with bending movements of the body, end flaps composed of horizontally stretchable elastic fabric secured to the outer ends of said brassière and down the sides of the corset to about the waist line, and means for securing said flaps under tension to the back of said corset.

3. A foundation garment for women comprising a combination corset and brassière, said corset having front and back sections composed of elastic fabric having a relatively long easy stretch and being capable of stretching only in a vertical

direction so as to prevent said corset from pulling the brassière down when the body is bent backward or forward, side sections connecting said front and back sections and composed of elastic fabric having a relatively short stretch and quick contraction and being capable of stretching only in a horizontal direction so as to tension said corset across the front and back of the body, a stiffening panel lining the interior of said front corset section and being connected thereto only at the vertical side edges and at a point adjacent the lower central edge of said brassière, elastic garter straps connected to the lower edges of said stiffening panel and said front corset section to permit said stiffening panel to slide up and down with bending movements of the body, end flaps composed of horizontally stretchable elastic fabric secured to the outer ends of said brassière and down the sides of the corset to about the waist line, and means for securing said flaps under tension to the back of said corset.

HILDEGARD WIPPERMAN.
